UNITED STATES PATENT OFFICE

125,130

DESIGN FOR A PHONOGRAPH CABINET

Sol Freedman, Los Angeles, Calif.

Application May 13, 1940, Serial No. 92,320

Term of patent 3½ years

To all whom it may concern:

Be it known that I, Sol Freedman, a citizen of the United States and a resident of the city of Los Angeles, in the county of Los Angeles and State of California, have invented a new, original, and ornamental Design for a Phonograph Cabinet, of which the following is a specification, reference being had to the accompanying drawing, forming part thereof.

In the drawing:

I claim:

The ornamental design for a phonograph cabinet, substantially as shown.

SOL FREEDMAN.
